UNITED STATES PATENT OFFICE.

HENRY S. BREWINGTON, OF BALTIMORE, MARYLAND.

DESIGN FOR A SECURING-BAR FOR TROUSERS-CLASPS.

SPECIFICATION forming part of Design No. 35,547, dated January 7, 1902.

Application filed December 9, 1901. Serial No. 85,292. Term of patent 7 years.

To all whom it may concern:

Be it known that I, HENRY S. BREWINGTON, a citizen of the United States, residing at Baltimore city, in the State of Maryland, have 5 invented and produced a new and original Design for a Securing-Bar for Trouser-Clasps; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention is a design for a securing-bar for trousers-clasps; and it consists of the shape and configuration hereinafter described, and illustrated in the accompanying drawings, in which—

20 Figure 1 is a view in perspective of a securing-bar embodying the design, and Fig. 2 is a transverse section of the same.

The reference-numeral 1 designates a bar of concavo-convex form in cross-section to present inclined sides 2 at the front of the 25 bar. The bar is bent at right angles at the points 3 and 4 and terminates in perforated heads 5, scalloped on their outer edges, as shown at 6.

The leading feature of the design is the concavo-convex form of the body of the bar, and minor features are the bends 3 and 4 and the 30 perforated scalloped heads.

I claim—

The design for a securing-bar for trousers- 35 clasps herein shown and described.

In testimony whereof I affix my signature in presence of two witnesses.

HENRY S. BREWINGTON.

Witnesses:

E. WALTON BREWINGTON,
ROBT. C. RHODES.
